(No Model.)

A. B. SMITH.
TAMPING HANDLE FOR SHOVELS.

No. 462,745.

Patented Nov. 10, 1891.

UNITED STATES PATENT OFFICE.

ABIA B. SMITH, OF PITTSBURG, PENNSYLVANIA, ASSIGNOR TO HUSSEY, BINNS & COMPANY, (LIMITED), OF SAME PLACE.

TAMPING-HANDLE FOR SHOVELS.

SPECIFICATION forming part of Letters Patent No. 462,745, dated November 10, 1891.

Application filed April 30, 1891. Serial No. 391,084. (No model.)

To all whom it may concern:

Be it known that I, ABIA B. SMITH, of Pittsburgh, county of Allegheny, State of Pennsylvania, have invented a certain new and useful

5 Improved Tamping-Handle for Shovels, of which the following is a true and exact description, reference being had to the accompanying drawings, which form a part of this specification.

10 My invention relates to shovel-handles of the kind known as "tamping-handles," and has for its object to provide a handle at once strong and light, and which will have no cavity in which dirt can be lodged.

15 My invention consists in forming a tamping-handle of an integral casting of malleable metal and with a hollow grasp-bar formed with one or more core-openings. In combination with this casting I provide a plug or plugs

20 adapted to fit in the opening or openings of the grasp-bar and when driven therein to close said openings, the outer surface of the plug being flush with the outside of the grasp-bar. Preferably the plug is formed as a lip on the

25 edge of the opening in the grasp-bar, the said lip being of such dimensions that when bent down into the opening it will close and fill the same. I also prefer in all cases to make the plug with a grooved edge, as this construction

30 I have found enables it to take a better hold upon the edges of the opening in the grasp-bar.

Reference is now had to the drawings, which illustrate my invention, and in which—

35 Figure 1 is a front view of the integral malleable casting of the tamping-handle having the opening in its front face. Fig. 2 is a side view of a similar handle having an opening at the end of the grasp-handle. Fig. 3 is a

40 cross-section on the line $x-x$ of Fig. 1, showing openings both in the front face and at the end of the grasp-handle. Fig. 4 is a plug adapted to fit in and fill the opening in the front of the handle; Fig. 5, a cross-section on

45 the line $y-y$ of Fig. 4; Fig. 6, a view similar to that of Fig. 3, but showing the plug formed as a lip on the edge of the opening. Fig. 7 is a view of an independent plug adapted to fit in and fill the opening at the end of the grasp-

bar; and Fig. 8 is a perspective view showing 50 plugs to fill openings both in the front and end of the grasp-bar, both formed as lips on the edges of the openings.

A is the handle, and B the grasp-bar, which is formed hollow, as shown in Figs. 3 and 6. 55

C is the opening in the front of the grasp-bar; C', the opening at the end thereof; D, an independent plug adapted to fill the opening C, said plug being formed with a groove d on its edges for the purpose above mentioned. 60

D' is a plug adapted to fit in the opening C'.

D² indicates the plug formed integral with the casting and has a lip on the edges of the openings formed therein. Where the independent plug is used it is simply driven into 65 the opening after the core has been extracted, and where the lip-plug is used it is only necessary to bend it down into the opening after the extraction of the core. The plugs after insertion are driven home by a few quick 70 blows, the groove d enabling it to take a strong hold upon the edges of the openings, and after the plug has been seated it is only necessary to smooth down the edges by filing or otherwise to fit the handle for use. The 75 handle thus made is strong, light, and durable, and free from the liability to catch and hold dirt, which is found so objectionable in many tamping-handles now in use. At the same time the handle is easily made and a relatively cheap construction. 80

Having now described my invention, what I claim as new, and desire to secure by Letters Patent, is—

1. A tamping-handle for shovels made of an 85 integral casting A, having a hollow grasp-bar formed with one or more core-openings, in combination with a plug or plugs adapted to close said opening or openings.

2. A tamping-handle for shovels made of an 90 integral casting A, having a hollow grasp-bar formed with one or more core-openings, in combination with a plug or plugs having grooved edges adapted to close said opening or openings.

3. A tamping-handle for shovels made of an integral casting A, having a hollow grasp-bar formed with one or more core-openings, in

combination with a plug or plugs cast as a lip on the edge of the openings and adapted to fill and close the openings when bent down.

4. A tamping-handle for shovels made of an integral casting A, having a hollow grasp-bar formed with one or more core-openings, in combination with a plug or plugs cast as a lip on the edge of the openings and having

grooved edges, said plug or plugs being adapted to close the openings in the grip when bent down.

ABIA B. SMITH.
